UNITED STATES PATENT OFFICE.

CHARLES G. TIEFEL, OF FAIRPORT, NEW YORK, ASSIGNOR TO TODD PROTECTOGRAPH COMPANY, OF ROCHESTER, NEW YORK, A CORPORATION OF NEW YORK.

CHECK-WRITER.

1,386,383.

Specification of Letters Patent.

Patented Aug. 2, 1921.

Application filed August 2, 1919. Serial No. 314,969.

To all whom it may concern:

Be it known that I, CHARLES G. TIEFEL, a citizen of the United States, residing at Fairport, in the county of Monroe and State 5 of New York, have invented certain new and useful Improvements in Check-Writers, of which the following is a specification.

This invention relates generally to printing machines and has particular reference 10 to machines for impressing limiting amounts upon checks and other negotiable instruments.

In the accompanying drawings, the improvements are shown applied to a word 15 printing check writer of a kind which is now well known on the market and which is fully shown and described in an application for U. S. Letters Patent filed April 23, 1917 by Libanus M. Todd, application No. 20 163,901, but this is an illustrative embodiment only. As will be clear later, the improvements can be applied in various forms and modifications to a large number of other figure and word printing machines known 25 in the art.

An object of the invention is to improve upon the construction shown and described in U. S. Letters Patent No. 793,249 issued June 27, 1905 to Libanus M. Todd. In that 30 patent there is disclosed a type carrier and platen construction whereby in printing the paper is cut, disrupted or shredded so as to facilitate impregnating the paper with ink. Amounts so shredded into the paper cannot 35 be completely erased, but attempts might be made to raise checks so printed by first removing some of the surface ink and then printing a larger amount over a smaller one. This would be difficult to do successfully, but such a raised check might pass 40 some one who was careless in his inspection. This invention provides a construction whereby machines having a universal platen, that is, a platen having a single impression 45 face coöperating with a number of different type forms, may be so constructed that attempts to impress a larger amount upon a smaller one will mutilate, cut or weaken the paper to such an extent that it will not bear 50 handling. This result has been obtained in certain prior art machines where there are different platen faces for different type, but as far as the applicant is aware, this is the first construction whereby the result can be

obtained in a machine having a universal 55 platen.

With this and other objects in view, the invention consists in the novel construction and combination of elements, the features of novelty of which are set forth in appended 60 claims, and one form of embodiment of which is hereinafter described with reference to the drawings which accompany and form a part of the specification.

Of said drawings:

Figure 1 is a front view of the assembled 65 machine used for illustration.

Fig. 2 is a left hand view of the same machine.

Fig. 3 is the same as Fig. 1 except that 70 parts are cut and broken away to expose the improved and other parts to view.

Fig. 4 is a section on the line 4—4 of Fig. 3.

Fig. 5 is a top plan view on a slightly en- 75 larged scale of the improved platen.

Fig. 6 is a section on the line 6—6 of Fig. 5.

Fig. 7 is a development of the type wheel 80 of the illustrative machine with the type faces constructed according to the invention.

Stated in a general way, the illustrative machine has a type carrier which is adjustable to different positions to set any one of a number of type lines thereon in position 85 to coöperate with a universal platen. Certain ones of the type forms are of about the same length and some of them resemble one another in their general outlines. For example, the word FIVE is about the same in 90 length as the word NINE and there is enough resemblance in the general outlines of the two to facilitate attempts to fraudulently alter checks by first making a partial erasure of the word FIVE and then printing 95 the word NINE over the erasure. While, as before stated, it is difficult to make such an alteration so successfully that it will not be detected, yet in machines constructed according to the Todd Patent No. 793,249, the lines 100 of shredding in the two impressions may coincide and, if enough care is used in making the change in amount, it might not be discovered until it was too late.

To prevent such frauds from being suc- 105 cessfully perpetrated, the improved type for printing words which are apt to be involved in making fraudulent changes are provided

with shredding projections extending across the type faces at different angles. In the example before referred to, the "FIVE" type have the projections extending in one direction, while the "NINE" type have the projections extending across their faces in a different direction.

Coöperating with the type is a universal platen having two sets of depressions to operate with the projections on the type. In the form shown in the drawings, these depressions are sets of grooves intersecting at an angle corresponding to the difference in direction of the two sets of projections on the type. The best results are obtained by a construction which permits having the grooves in the platen intersect at a right angle, although variations from that angle may be made without greatly affecting the result.

The machine used for illustration has an outside casing comprising a base 10 and hood 11 separated at the front to form a work receiving slot 12.

25 Journaled in the hood 11 above the slot is a shaft 13 to which is secured a type carrier or support 14 having a plurality of lines of type 15 for printing different words. Fastened to the shaft 13 is a knob 16 for use in turning the type carrier to different positions. An indicator 17 moving with the type carrier coöperates with an index 18 to guide the operator. When any character on the indicator is set opposite the index, 30 the type 15 for printing the corresponding word will be above a universal platen 19. Any suitable mechanism may be employed for alining the type with the platen. A very satisfactory one is shown in application No. 163,901, referred to above.

35 The platen 19 is adjustably supported by a lever 21 pivoted upon a rod 22. The rear end of the lever is connected by a link 23 to short arms 24 fastened to a rock shaft 25 extending across the rear of the machine. The arms 24 and link 23 form a toggle so that when the shaft 25 is rocked counter-clockwise (Fig. 4), the platen 19 will be raised to press the paper against the type 40 face resting above the platen. A spring 26 tends at all times to hold the platen 19 in the position shown and returns it to that position when the shaft 25 is released.

45 The rock shaft 25 is moved to force the platen against the type by means of an operating handle 27 and the type are inked by engagement with an ink roll 28 as the type carrier is rotated to different positions in the course of selecting the type to be 50 printed from.

55 As shown in Fig. 7, the word type forms of the illustrative machine are of different lengths and the impressions from their faces will occupy correspondingly different 60 extents of surface. It is necessary after print-

ing one of the words to feed the paper a distance corresponding to the length of the imprint so as to present a fresh surface for the next impression. This is effected by a flanged feeding element 31 attached to a shaft 32 extending from front to rear in the base 10. The front of the base 10 has a vertical slot (not shown) surrounding the shaft 32 so that the forward end of the shaft may be depressed against the tension of a spring 33 to carry the feeding element 31 away from coöperating rollers 34 a distance sufficient to permit inserting and removing the paper. A knob 35 fastened to the shaft 32 provides a means for both depressing the shaft and turning it to different positions. When the shaft is turned, the feeding element 31 coöperates with the rollers 34 to feed the work between the platen and type carrier, the distance of the feed depending upon the length of the word last printed.

65 To print an inscription on a check the knob 16 is first turned to a position where the character 36 (Fig. 7) is at the printing line and the handle 27 is then operated to make an impression. The knob is turned to select the different words to make up the inscription and as each is brought to the printing point, the handle 27 is operated to make an impression. Between the printing 70 impressions the feeding device 35 is operated to feed the paper so that the words will follow one another in correct relation and with the proper word spacing gap between them.

75 As shown in Fig. 7, some of the type forms have ridges or corrugations extending in one direction across their faces, while the rest of the type are provided with similar ridges or corrugations extending in a different direction, and the universal platen 19 is, as shown in Fig. 5, constructed with two sets of grooves intersecting at approximately a right angle. One set of grooves is to register with and receive the type ridges running 80 at one angle, while the other set of grooves is to receive the ridges running at the other angle. The construction is such that no matter what type is positioned at the printing point, the platen will accommodate the 85 ridges on the type so that the shredding function will be performed along practically continuous lines as shown in Patent No. 793,249, hereinbefore mentioned. This may be facilitated to a certain extent by blunting the 90 apices of the ridges or projections, as illustrated in Fig. 6, but satisfactory results are obtained without doing this, although the sharp points are more apt to mutilate the type if impressions are attempted without 95 having the type in correct registration with the platen.

100 With a construction such as described, if to use the same example as before, the word FIVE is first printed and then an attempt 105

made to superimpose an impression of the word NINE, the ridges in the word FIVE will coöperate with the universal platen 19 to cut or shred the paper in substantially 5 the same way as if the platen had but a single set of grooves. The same thing is true in printing the word NINE. But as the shredding projections on the FIVE and NINE type are at different angles (see Fig. 10 7), it is clear that printing the word NINE over the word FIVE will result in shredding the paper in two directions, one shredding intersecting the other, so that the paper will be so nearly destroyed where printed as 15 to prevent negotiation of the instrument.

The ridges on each type form may be disposed at either angle desired with reference to the type for other words which are likely to be employed in making raises. As another example, the word EIGHTY is one 20 letter longer than the word EIGHT, but if the word EIGHTY is printed over the word EIGHT, the first five letters will coincide. If, through careless operation, a 25 sufficient space is left after printing the word EIGHT, a check might be raised by simply over-printing the word EIGHTY. As will be seen by again referring to Fig. 7, the ridges on the type for printing these 30 two words run in different directions so that the effect of such a superimposed printing will be to destroy the paper.

From the foregoing, it is clear that the construction herein shown and described is 35 admirably adapted to fulfil the objects hereinbefore stated, but it is not the desire to be limited to any one embodiment. The inventive idea is one which is capable of use in various forms and modifications in a number 40 of different machines for different purposes, these various embodiments all coming within the scope of the claims which follow.

What is claimed is:

1. In a machine of the class described, a 45 printing couple comprising a universal platen and a plurality of printing type, said platen and type having their impression faces constructed to shred the paper at different angles for different values, and means 50 for operating the printing couple to print any desired values.

2. In a machine of the class described, a printing couple comprising a universal platen and a plurality of word type forms 55 for printing words representing different values, the platen and type having their impression faces constructed to shred the paper at different angles for different values, and means for operating the printing couple to print from any desired type form.

3. In a machine of the class described, the combination with a type carrier provided

with a plurality of printing type, some of which have shredding projections extending 65 in one direction across their faces and others having such projections extending across their faces in a different direction, a universal platen having its impression face recessed to register with both sets of projections, and means for effecting printing engagement of the platen and any desired type.

4. In a machine of the class described, the combination with an adjustable type support 75 provided with a plurality of type forms, some of which have elongated shredding projections extending across their faces in one direction and the other type having similar projections extending across their 80 faces in a different direction, a universal platen having depressions to register with and receive either of the two sets of shredding projections on the type, and means for adjusting the type support to position any 85 desired type opposite the platen.

5. In a machine of the class described, the combination with an adjustable type carrier provided with printing type, some of which have elongated shredding projections extending across their faces at one angle and the others having projections extending across their faces at a different angle, of a universal platen having its impression surface provided with recesses to register with 90 and receive all of the projections on the type, and means for effecting a relative printing movement of the type support and platen.

6. In a machine of the class described, the combination with a type carrier provided 100 with a plurality of type, some of which have ridges extending in one direction across their printing faces and others having such ridges extending across their printing faces at a different direction, a universal platen having 105 its impression face formed with intersecting sets of grooves to receive either set of ridges on the type, and means for effecting a printing engagement of the platen and any desired type.

7. In a machine of the class described, the combination with a universal platen having its impression face provided with intersecting sets of grooves, of a type support provided with a plurality of type, some of which 115 have their printing faces ridged to coöperate with one set of grooves in the platen and the rest ridged to coöperate with the other set of said grooves, means for applying ink to the type, and means for operating the 120 platen and type carrier to print from any desired type.

In testimony whereof I hereby affix my signature.

CHARLES G. TIEFEL.
